UNITED STATES PATENT OFFICE.

WILLIAM E. STEVENS, OF NEW HAVEN, CONNECTICUT, ASSIGNOR TO
SARGENT & CO., OF SAME PLACE.

DESIGN FOR COFFIN-HANDLE SOCKETS.

SPECIFICATION forming part of Design No. 11,791, dated May 25, 1880.

Application filed April 26, 1880. Term of patent 14 years.

To all whom it may concern:

Be it known that I, WM. E. STEVENS, of New Haven, in the county of New Haven and State of Connecticut, have invented a new 5 Design for Coffin-Handle Sockets; and I do hereby declare the following, when taken in connection with the accompanying drawing and the letters of reference marked thereon, to be a full, clear, and exact description of the 10 same, and which said drawing constitutes part of this specification, and represents a face view.

This invention relates to a design for socket or base for coffin-handles—that is to say, that 15 part by which the handle is attached to the coffin; and it consists in the configuration and ornamentation, as shown in the accompanying illustration.

The general outline of the base is in the

form of a four-pointed star, on the center of 20 which the ears *a*, to which the handle-lever is attached, are arranged, with ornamentation surrounding on the surface of the base. The edge of the base between the points is ornamented by a series of notches or indentations, 25 which give the appearance of a mat upon which the star rests, and as shown in the accompanying illustration.

I claim—

The design for coffin-handle socket, consisting of the star-shaped base with notched or indented projections between the points of the star, as shown in the accompanying illustration.

W. E. STEVENS.
